MILK BOTTLE HOLDER

Clinton E. Herring, Hunlock Creek, and Herbert S. Parsons, Nanticoke, Pa., assignors to said Herbert S. Parsons, Nanticoke, Pa.

Application November 29, 1932, Serial No. 644,892

3 Claims. (Cl. 232—41)

This invention relates to an improved milk bottle holder of the type embodying a box-like casing adapted to be securely anchored to a relatively stationary support and constructed to facilitate insertion of the full bottle of milk by the delivery man and subsequent expeditious and convenient removal of the bottle by the housewife.

We are aware of the fact that the art to which the invention relates is both active and well-developed. Therefore we desire it understood that the present invention constitutes a relatively novel contribution to the art characterized by noteworthy and readily recognizable structural distinctions carefully selected and mechanically co-ordinated to provide an acceptable addition to the art and trade.

The specific structural features utilized for accomplishing these results will become more readily apparent from the following description and the accompanying illustrative drawing of the preferred embodiment of the invention.

In the drawing:

Figure 1 is a front elevation with portions broken away and shown in section, the section being on the line 1—1 of Figure 2.

Figure 2 is a view at right angles to Figure 1, the section being taken on the plane of the line 2—2 of Figure 1.

Figure 3 is a horizontal sectional view taken approximately on the plane of the line 3—3 of Figure 1.

As before implied, the casing 4 is of general box-like form and is here shown as vertically elongated and embodying a back wall 5, a side wall 6 and an opposed side wall 7, the latter wall being formed along its front vertical edge with an inturned reinforcing and retaining flange 8. The flange 8 serves as a keeper for the projectible retaining bolt 9 of an appropriate key-controlled lock 10 carried by the front door 11. The door is hinged as at 12 to the front edge of the wall 6 and has its free swingable edge portion abutting the flange 8 and provided with an extension lip 13 to provide an effective closure.

The upper end of the walls 6 and 7 are provided with inturned flanges 14 and 15. The bottom 16 is in the form of a plate which is hingedly attached to the frontal edge portions of the walls 6 and 7 as indicated at 17 in Figure 2. This bottom effects a complete closure for the lower portion of the casing.

We next call attention to the top closure which is made up of a pair of companion sections 18 and 19 which provide a complete closing lid for

the top. These sections 18 and 19 are pivotally mounted on supporting rods 20 and normally held in closed positions through the instrumentality of appropriate coiled springs 21. The springs serve to swing the lid sections 18 and 19 out against the retaining or stop flanges 14 and 15.

Means is provided for preventing depressing of the lid sections 18 and 19 which means comprises a substantially L-shaped trigger 22 having its long arm portion 23 pivoted to the side wall 6 as indicated at 24. The short arm 25 functions as a cam-like retention finger and is movable from the full-line position shown in Figure 2 to the dotted line position in which latter position the finger 25 underlies the free edge portions of the lid sections 18 and 19 to prevent said sections from being forced inwardly whereby to prevent unauthorized withdrawal of the bottle of milk 26 after it has been placed completely in the casing by the milk man. This is accomplished through the instrumentality of an elongated link 27 which is pivotally connected at its upper end to the arm 23 of the trigger 22.

The lower end of this link is pivoted as at 29 to the free swingable end portion of the hinged bottom 16. Consequently, by placing the bottom of the milk bottle against the lids 18 and 19 and forcing it downwardly said lids are spread apart sufficiently to permit the bottle to be dropped into the container.

As the bottle comes into engagement with the hinged bottom 16 it swings the bottom from the full line position in Figure 2 downwardly to the dotted line position shown in the same figure. At the same time, it acts upon the trigger 22 through the agency of the link 27 to swing the finger 25 underneath of the free swingable edge portions of the lid sections 18 and 19 to prevent unauthorized withdrawal of the bottle.

We also call attention to a coil spring 30 which co-operates with the pivot 24 and trigger to normally return the trigger to the full line position after the full bottle of milk has been removed by an authorized agent from the casing by way of the front door 11. Consequently, the bottle of milk is inserted by the milk man and automatically locked in place and cannot be removed until the door 11 is opened.

Inasmuch as the door is provided with a key-controlled lock this makes it possible for the attendant of the house to have sole access to the milk.

Manifestly, in Figure 2, the full lines show the

normal positions of the parts 16, 27 and 22. The dotted lines show the positions assumed by these features after the milk bottle 26 is put in position by the milk man. Thus, broadly recited, the retaining means for the lid sections 18 and 19 is bottle-actuated.

It is thought from the foregoing description that the advantages and novel features of the invention will be readily apparent. It is to be understood that changes may be made in the construction and in the combination and arrangement of the several parts provided that such changes fall within the scope of the appended claims.

15 We claim:

1. A milk bottle holder comprising a vertically elongated cabinet-like casing open top and front, a hinged door for closing the front provided with locking means, a hinged bottom, a pair of hingedly mounted spring-returned lid sections constituting a closure for the top of said casing, said lid sections being swingable inwardly and downwardly to permit the bottle of milk to be inserted into the casing, an L-shaped retainer pivotally mounted in said casing adjacent the upper end thereof and adapted to underlie the meeting edge portions of said lid sections to hold the lid sections in a predetermined position, a link connection between said L-shaped member and free swingable end portion of said bottom.

2. A milk bottle holder comprising a vertically elongated cabinet-like casing open at its bottom and top and front, a hinged door for closing the front provided with locking means, a hinged bottom for closing the bottom of the casing, a pair of hingedly mounted spring-returned lid sections constituting a closure for the top of said cas-

ing, said lid sections being swingable inwardly and downwardly to permit the bottle of milk to be inserted in the casing, an L-shaped retainer pivotally mounted in said casing adjacent the upper end thereof and adapted to underlie the meeting edge portions of said lid sections to hold the lid sections in a predetermined position, a link connection between said L-shaped member and free swingable end portion of said bottom, and spring means associated with the pivoted portion of said L-shaped member to normally return said L-shaped member to a predetermined position at which time said hinged bottom is elevated into the casing.

3. A milk bottle holder comprising a vertically elongated cabinet-like casing open at its front and at its bottom and top, a hinged bottom for closing the bottom of said casing, a hinged door closing the front of the casing, locking means for said door, a pair of lid sections hingedly mounted in the upper portion of said casing to effect a closure for the top of the casing, spring means for returning said lid sections to a normal closed position, said lid sections being depressible inwardly and downwardly to permit the bottle to be inserted, an L-shaped trigger having one arm portion pivotally connected to one side wall of the casing adjacent the upper end thereof at a point intermediate the ends of said arm, the short arm of said L-shaped trigger constituting a retaining finger to underlie the meeting edges of said lid sections, a return spring connected with the pivoted portion of said trigger, a link pivoted to the trigger and pivoted at its lower end to the free swingable edge portion of said bottom.
